Patented Dec. 30, 1924.

UNITED STATES PATENT OFFICE.

ALDO CURIONI, OF NEW ROCHELLE, NEW YORK, ASSIGNOR TO MAURICE LEVY,
OF NEW YORK, N. Y.

METHOD OF SEWING POWDER PUFFS.

Application filed September 21, 1922. Serial No. 589,555.

To all whom it may concern:

Be it known that I, ALDO CURIONI, a subject of the King of Italy, residing at Larchmont Wood, New Rochelle, in the county of Westchester and State of New York, have invented certain new and useful Improvements in Methods of Sewing Powder Puffs, of which the following is a specification.

10 My invention relates to a new and improved method for the sewing of powder puffs.

One of the objects of my invention is to provide a new and useful method which shall be capable of use with the large automatic machines shown in my copending applications Serial No. 539,101 filed February 25th, 1922, and Serial No. 463,018 filed April 20th, 1921.

20 In making powder puffs from lamb's wool I have found that it is desirable and necessary in order to secure uniform production, to compact the material from which the puffs are manufactured, namely lamb's wool or the like, at the edges thereof and while the said material is being sewed together. I have also found it highly desirable to push the edges of the nap of said material inwardly while the said sewing operation is being performed. These additional operations cause the edge of the completed puff to have a neat and finished appearance.

Other objects of my invention will be set forth in the following description and drawings which illustrate a mechanism suitable for practicing my method.

Fig. 1 is a side elevation of a mechanism suitable for practicing my method.

40 Fig. 2 is a section on the line 2—2 of Fig. 1.

Fig. 3 is an enlarged view in elevation partially in section.

Fig. 4 is a section on the line 4—4 of Fig. 1.

45 Fig. 5 is a section on the line 5—5 of Fig. 3.

Fig. 6 is an enlarged sectional view of one of the holding and compacting fingers.

50 Two discs of fabric D are cut by any suitable means and placed one on top of the other with the sides having the naps thereon adjacent each other as clearly illustrated in Figs. 1 and 3.

55 These superposed discs D are preferably

held upon needles 1 mounted upon the revoluble carrier disc 2, which is carried by the holder 3, but they may be held by any suitable means. I have not illustrated the automatic mechanism for cutting out the 60 discs D and placing them upon the needles 1 because this is thoroughly set forth in my copending application filed February 25th, 1922, and this could be done by hand, if desired.

65 The edges of the discs D are sewed together by any suitable sewing machine, of which a conventional type is illustrated in the drawings. For a brief description of the said sewing machine, I may state that 70 this has the rocker arm 2 pivoted at 3 to the frame 4 and that the needle N is secured to the ordinary needle bar 5. The presser foot P, feed dog, etc., of the sewing machine may be of any suitable type. 75 The sewing machine is driven by any ordinary belt 6 which passes around any ordinary pulley 7 mounted upon the shaft 8.

80 The machine is provided with the ordinary tension means 8' and stitch regulating means 9 and a stopping device 10 which are sufficiently described in my said application Serial No. 539,101 and in themselves form no part of my present invention.

85 While the revoluble holding disc 2 is being revolved, and while the sewing operation is being performed the nap of the material of which the discs D are formed is continuously pushed inwardly by a pusher 11. For this purpose the shaft 8 has the cam 12 provided with a cam groove into which fits the roller 14 connected to the pusher 11. As clearly shown in Fig. 2, the end of the pusher bar 11 is provided 90 with a series of teeth 15 so as to more efficiently operate upon the loose fluffy material with which it contacts. The pusher bar 11 is mounted in guides in the frame 16. The frame 16 is mounted in the main 95 machine frame 4 by means of screws 17. The plate 18 is connected to the frame 16 by means of screws 17 and 19 and this plate 18 has two holding bars or fingers 20 and 21 pivoted upon the screws 19. 100 These holding bars 20 and 21 are pivoted so that they can be oscillated in the vertical plane and their flat ends are provided with a series of teeth 22 as clearly shown in Fig. 6. The pusher bar is provided with two 105

rollers 23 and 24 revolvably mounted upon projections thereof and these rollers co-operate with the inclined surfaces found at the rear ends of the holding bars 20 and 21 so that the movement of the said pusher bar 11 to the left of the position shown in Fig. 3 tends to move the teeth 22 of the said holding bars 20 and 21 towards each other. The holding bars 20 and 21 are normally separated by the expansion spring 24'.

The operation of my device is as follows: The holding discs are continuously revolved while the needle bar is continuously reciprocated in the well known manner. The holding bars 20 grip and hold and compress the fabric just before the needle penetrates the fabric so that the fabric cannot buckle or move because of the action 15 of the pusher bar 11 which operates to push the soft fluffy material of the nap of each disc inwardly just before the needle penetrates the fabric to form the stitch.

Hence during the sewing operation the 20 two discs of fabric are compressed and the nap of the material at the periphery thereof is forced inwardly. The holding bars 20 and 21 are moved in opposite directions to release the fabric and the pusher bar 11 is 25 also moved outwardly to release the fabric just before the needle N is moved upwardly to release the fabric. Hence the first operation upon the fabric is to grip it between the holding bars. The next operation is to 30 inwardly push the nap of the fabric. The next operation is the beginning of the formation of the stitch by the downward movement of the needle. Then the pusher bar 11 is moved in a direction away from the 35 needle, the holding bars are opened by the compression spring 24' and the needle end leaves the fabric with the stitch completely formed.

The member 11 may at all times project somewhat between the discs D so that as the 45 said discs are continuously revolved the nap is continuously smoothed by the said member 11, although my invention is not limited to this feature. As disclosed in my former applications, the discs D are partially sewed together with their nap sides or surfaces adjacent each other, and the partially sewed puff thus formed is then turned so as to expose the naps of discs D. The sewing 50 is then completed.

I have shown a preferred embodiment of my invention but it is clear that numerous changes and omissions can be made without departing from its spirit and where I refer to the parts herein either in the description 55 or the claims by means of numerals, I do not wish to be limited to the specific embodiment herein disclosed.

I claim:—

1. A method of sewing a powder puff 65 which consists in sewing together corresponding portions of two discs of fabric of which said puff is composed and each of which has a base and a nap surface while said nap surfaces are facing each other, 70 while inwardly pushing the naps of said discs as the stitches are formed so that said stitches do not encircle the upright nap fibres, then turning the bag-like article 75 formed by sewing together the said corresponding portions of said discs until the bases of said discs face each other, and then connecting the unsewed portions of said discs.

2. A method according to claim 1 in 80 which the edges of said discs are held and pressed together during the sewing together of said corresponding disc portions.

In testimony whereof I hereunto affix my signature.

ALDO CURIONI.
